UNITED STATES PATENT OFFICE.

FRANK E. MATTESON, OF LOS ANGELES, CALIFORNIA.

LOCK-SWITCH.

1,242,013.

Specification of Letters Patent.

Patented Oct. 2, 1917.

Application filed July 3, 1916. Serial No. 107,286.

To all whom it may concern:

Be it known that I, FRANK E. MATTESON, a citizen of the United States, residing at Los Angeles, in the county of Los Angeles 5 and State of California, have invented new and useful Improvements in Lock-Switches, of which the following is a specification.

This invention is an electric switch that resembles the combination lock of a safe in 10 general appearance and method of operation, though the internal mechanism is entirely different. The objects sought and accomplished by this mechanism are; to close an electric circuit by turning the knob a 15 specified combination of turns; to break the circuit by turning the knob out of that position, and to so protect the mechanism itself against tampering by thieves, that it cannot be taken apart except by a definite 20 combination of turns of the knob.

The switch may be used on light circuits and other electric service not too heavy for this kind of switch construction, but the chief purpose for which it is intended, is to 25 safe-guard the automobile against thieves.

The idea of a series of disks or plates (made of material that is a nonconductor of electricity and pierced in places with conductors) working one upon the other by the 30 manipulation of the knob, to bring the conductors into alinement, is an important feature of this invention. The matching of slots with lugs between the outer edge of the knob plate and inside of case, also be- 35 tween outer edge of movable disks and inside of case, (all of which slots and lugs are concealed) to permit disassembling of parts when said lugs and slots are brought into proper alinement by definite movements 40 of the knob, adds materially to the practicability of the invention.

Figure 1 is a plan view of a lock switch embodying the principles of my invention, as seen looking in the direction indicated by 45 the arrow —1— in Fig. 2.

Fig. 2 is a vertical central section as on the lines 2—2 of Figs. 1 and 3.

Fig. 3 is an enlarged horizontal sectional detail stepped down from the top to the 50 various planes indicated by the line 3—3 in Fig. 2.

Fig. 4 is a perspective of the base with the other parts removed.

Fig. 5 is a perspective of the rotating insulating disk.

Fig. 6 is a perspective of the knob looking upwardly from the bottom.

Fig. 7 is a fragmentary enlarged sectional detail on the line —7— of Fig. 4 and showing a pair of brushes and a conductor. 60

The annular base 1 has a graduated dial 2 upon its upper face around the chamber 3 and has an inwardly extending rim 4 at the bottom of the chamber, and a series of inwardly projecting retaining lugs 5 extend 65 inwardly from the vertical wall 6, equally spaced apart around the chamber and spaced from the rim 4, and a second series of inwardly projecting lugs 7 extends inwardly from the wall 6 in vertical alinement with the lugs 5. The rim 4 extends inwardly farther than the lugs 5 and 7. The bottom insulating disk 8 has notches 9 to pass the lugs 5 and 7, and said disk fits in the bottom of the base with its lower face 70 flush with the lower face of the base, and fits against the rim 4. The disk 8 is rotatable in the chamber until properly adjusted, and then it is secured rigidly in place by screws 10 inserted downwardly through 75 the disk and screw-seated in the rim 4. A circular recess 11 is formed in the upper face of the disk 8 and a nut 12 is embedded in the lower face of the disk 8 at its center. Electric conductors 13 and 14 are inserted 80 through brushes 15 and 16 recessed into the lower face of the disk 8, and through the disk 8, and through brushes 17 and 18 in the recess 11.

The second insulating disk 19 has notches 90 20 in its periphery to register with the lugs 5 and 7. One-half of the thickness of the disk is cut away around the periphery to produce the rim 21 adapted to fit between the disk 8 and the lugs 5. A central key-hole 22 is formed through the disk 19 with an integral key-lug 23 extending into the key-hole. Conductors 24 and 25 are fixed 95 through the disk 19 in position to register with the brushes 17 and 18. 100

The knob 26 has a lower rim 27 provided with notches 28 for passing the lugs 7 so that the rim 27 will fit below the lugs, and an upper rim 29 fitting above the lugs 7 flush with the dial 2. A circular recess 30 105 is formed in the lower face of the knob 26 concentric to the rim 27. A central bore 31 is formed vertically through the knob, and a screw-seat 32 is formed at the lower end of the bore 31. 110

The third insulating disk 33 is fitted into the recess 30 and has a conductor recess 34 in its upper face and brush recesses 35 and 36 in its lower face. Brushes 37 and 38 are 5 mounted in the recesses 35 and 36 in position to register with the conductors 24 and 25. Conductors 39 and 40 extend through the disk 33 and hold the brushes 37 and 38 in place. A conductor wire 41 connects the 10 conductors 39 and 40 in the recess 34.

The key 42 has a head 43 upon its lower end, said head extending into the recess 11, and the key is inserted upwardly loosely through the key-hole 22, tightly through a 15 central opening 44 in the third disk 33, and is jammed into the screw-seat 32 so as to be rigid with the knob. The lip 45 extends from the key 42 and fits tightly in the key-seat 46 of the disk 33 and loosely in the 20 key-hole 22, so that as the key is rotated one way or the other the lip 45 will engage the key-lug 23 to rotate the disk 19.

The removable set-bolt 47 has a head 48 fitting against the top of the knob and the bolt extends through the knob 26 through the key 42 and through the disk 8 into the nut 12 so that by manipulating the head 48 the bolt may be tightened in the nut to hold the knob from being rotated and so that 30 by loosening the bolt the parts are free to rotate to work the combination. A pointer 49 upon the face 50 of the knob registers with the indications upon the dial as a guide in working the combination.

35 When the combination is known, the knob is rotated one way until the notches 20 register with the lugs 5, then the knob is rotated the other way until the notches 28 register with the lugs 7, the set-bolt 47 is 40 removed, and the knob carrying the second insulating disk, the key, etc., may be removed. Again, when the combination for closing the circuit is known, the knob 26 is rotated until the conductors 24 and 25 register with the brushes 17 and 18, then the 45 knob is rotated the other way until the brushes 37 and 38 register with the conductors 24 and 25, and the circuit is closed. Any movement of the knob from this position breaks the circuit. The brushes 15 and 50 16 are the lower ends of the terminals of the switch, one end of the cut wire being brought to the brush 15 and the other end to the brush 16. The rims 21 and 27 interlock with the lugs 5 and 7 so as to hold the 55 parts together except when the proper combination is worked to bring the notches 20 and 28 together. The rim 27 will hold the parts while the lugs 5 are passing the notches 20 and the rim 21 will hold while the 60 notches 28 are passing the lugs 7.

Various changes may be made in the arrangement and construction without departing from the spirit of my invention as set 65 up in the following claims.

I claim:

1. In a lock switch, a base having a circular chamber open at the top, insulated terminals fixed at the bottom of the chamber, an insulating disk rotatably mounted in the chamber and having conductors adapted to contact with the terminals, a knob rotatably mounted in the chamber and having insulated connected terminals adapted to contact with the conductors of the disk; interlocking notched rims and lugs upon the base and the insulating disk and the knob, a key rigid with the knob, and a key-lug rigid with the rotatable disk. 75

2. In a lock switch, a base having a circular chamber open at the top, and a dial around the chamber, insulated terminals fixed at the bottom of the chamber; the base being rotatable relative to the terminals before fixing; an insulating disk rotatably mounted in the chamber and having conductors adapted to contact with the terminals, a knob rotatably mounted in the chamber and registering with the dial and having insulated connected terminals adapted to 80 contact with the conductors of the disk; permutation interlocking notched rims and lugs upon the base and the insulating disk and knob; a key inserted upwardly through the disk and fixed in the knob and having a head 85 to hold the disk against the knob, and a key-lug rigid with the disk to be engaged by the key. 90

3. In a lock switch, a base having a circular chamber open at the top and a dial 100 around the chamber and a rim extending inwardly at the bottom of the chamber, an insulating disk inserted downwardly in the chamber against the rim, said disk and base being relatively rotatable before fixing, 105 means fixing the disk rigid with the base, terminals extending through the fixed disk, a second insulating disk rotatably mounted in the chamber upon the first disk and having conductors adapted to contact with the 110 terminals, a knob rotatably mounted in the top of the chamber and registering with the dial and having insulated connected terminals adapted to contact with the conductors of the second disk; interlocking notched 115 rims and lugs upon the base and the second insulating disk and the knob; a key rigid with the knob, and a key-lug rigid with the second disk. 120

4. In a lock switch, a base having a circular chamber open at the top, insulated terminals fixed at the bottom of the chamber, an insulating disk rotatably mounted in the chamber and having conductors adapted to contact with the terminals, a knob rotatably mounted in the chamber and having insulated connected terminals adapted to contact with the conductors of the disk; interlocking notched rims and lugs upon the base and the 125 disk and knob; a key rigid with the knob, a 130

- key-lug rigid with the rotatable disk; a nut fixed at the bottom of the chamber, alined openings extending upwardly from the nut through all the parts to the top of the knob, 5 and a set-bolt inserted downwardly from the top of the knob and screw-seated in the nut and having a head to engage the top of the knob.
5. In a lock switch, a base having a circular chamber open at the top and a dial around the chamber, insulated terminals fixed at the bottom of the chamber; the base being rotatable relative to the terminals before fixing; an insulating disk rotatably 10 mounted in the chamber and having conductors adapted to contact with the terminals, a knob rotatably mounted in the chamber and registering with the dial and having insulated connected terminals adapted to 15 contact with the conductors of the disk; permutation interlocking notched rims and lugs upon the base and the disk and the knob; a key inserted upwardly through the disk and fixed in the knob and having a head to hold 20 the disk against the knob, a key-lug rigid with the disk to be engaged by the key; a nut fixed at the bottom of the chamber, alined openings extending upwardly from the nut through all the parts to the top of the knob, 25 and a set-bolt inserted downwardly from the top of the knob and screw-seated in the nut and having a head to engage the top of the knob.
- from the top of the knob and screw-seated in the nut and having a head to engage the top of the knob.
6. In a lock switch, a base having a circular chamber open at the top and a dial 35 around the chamber and a rim extending inwardly at the bottom of the chamber, an insulating disk inserted downwardly in the chamber against the rim; said disk and base being relatively rotatable before fixing; 40 means fixing the disk rigid with the base, terminals extending through the fixed disk, a second insulating disk rotatably mounted in the chamber upon the first disk and having conductors adapted to contact with the terminals, a knob rotatably mounted in the top of the chamber and registering with the dial and having insulated connected terminals adapted to contact with the conductors 45 of the second disk; means for holding the knob in the base; a key rigid with the knob, a key-lug rigid with the second disk; a nut fixed at the bottom of the chamber, alined 50 openings extending upwardly from the nut through all the parts to the top of the knob, and a set-bolt inserted downwardly from the top of the knob and screw-seated in the nut and having a head to engage the top of the knob. 55
